TEXTILE MACHINERY CLEANING APPARATUS

William B. Hodge, Charlotte, N. C., assignor to
 Parks-Cramer Company, Fitchburg, Mass., a
 corporation of Massachusetts

Application May 23, 1938, Serial No. 209,545

6 Claims. (Cl. 118—19)

This invention relates to a cleaning apparatus for textile machinery such as spinning frames, drawing frames and the like, and more especially to that system which will direct draughts of air to all portions of the machine to remove lint and foreign substances therefrom.

Heretofore various devices have been employed for removing lint and other substances from textile machinery. It has been common practice to direct blasts of air downwardly upon the creel board, drawing rolls, and thread board, of the spinning frames, and thereby remove the lint from the upper side thereof. The portions of the frames which were not subjected to the draughts of air were not cleansed, and consequently the lint would cling to portions of the machinery below the thread board. This defect in cleaning is particularly noticeable in the lower portion of textile machines where many shafts, rods and cylinders are present to obstruct the downwardly directed draughts of air from the cleaner which is usually disposed thereabove.

It is, therefore, an object of this invention to provide a cleaning system for textile machinery comprising means for producing a plurality of draughts of air which are directed upon opposed sides of the members of the textile machine to thereby expose all surfaces to the necessary draughts for cleaning purposes.

It is another object of this invention to provide an apparatus for cleaning textile machinery comprising the combination of a travelling cleaner disposed above the textile machine for directing draughts of air downwardly, a plurality of fans disposed in the lower portion of the machine, and adapted to direct draughts of air longitudinally of the machine, and in the direction that the cleaner is travelling, together with a suction outlet disposed at the remote end of the textile machine for collecting the dust and lint removed from both sides of the textile machine, by the upper and lower fans. By locating one fan above the machine and another below, it is evident that the draughts from the respective fans will converge upon opposed sides of the members of the machine and thereby cooperate together in directing this lint to a suction opening, which will withdraw it from the room. This suction opening is partially assisted by the normal excess pressure within the room in which the textile machine operates. It is a well known fact that the pressure within the room, under normal working conditions, is in excess of the outside atmospheric pressure, consequently there will be a tendency for the room pressure to force the

room air into the suction opening and thereby supplement the work of the suction fan.

It is a further object of this invention to provide means for encasing the lower sides of spinning frames and the like and leaving air inlets at the top and bottom of the encasing means, and providing fans disposed within the encased portion of the machine for blowing lint from the lower portions of the machine, together with suction means communicating with the upper surface of the floor beneath the machine, so that where travelling cleaners are used above the machine, the lint which falls onto the floor in the aisles will be drawn beneath the machine and removed by the suction means, and also the lint which passes from the upper part of the machine, into the lower encased part of the machine, will be effectively removed from the portions of the machinery.

Some of the objects of the invention having been stated, other objects will appear as the description proceeds when taken in connection with the accompanying drawings, in which—

Figure 1 is a sectional view through the floor of a building showing in elevation a spinning frame embodying my invention;

Figure 2 is a sectional plan view taken along the line 2—2 in Figure 1;

Figure 3 is a vertical sectional view taken along the line 3—3 in Figure 1;

Figure 4 is a schematic plan view showing the present invention employed in combination with a plurality of textile machines.

Referring more particularly to the drawings, the numeral 10 indicates the floor of a building upon which is mounted a textile machine such as a spinning frame 11, said frame comprising end frames 12, intermediate sams 14, creel boards 16, sets of drawing rolls 17 and 18, ring rails 19, bolster rails 20, and cylinder 21. This cylinder is secured on shaft 22, the ends of which are journaled in end frames 12. Suitable packages of yarn 25 are mounted on the creel boards from which it is drawn between rolls 17 and 18 in the form of strands 26, after which it is spun upon other packages 27. Each package 27 is mounted upon a spindle assembly 28 which in turn is secured in bolster rail 20. Rotary motion is imparted to package 27 by means of a tape 31, which tape is also mounted upon cylinder 21. The above enumerated parts are conventional, but it is deemed necessary to disclose this much of the conventional structure in order to more clearly illustrate the utility of my present invention.

As heretofore stated, the yarn which is being processed allows much lint and loose particles to be dropped therefrom and upon the framework of the machine. Some means must be provided for removing this lint in order to prevent batches of this lint from accumulating upon the framework and dropping into the processed yarns, and thereby create a defective product. This lint has been removed with a great degree of success by a travelling cleaner such as disclosed in my prior patent, No. 2,011,763, issued on August 20, 1935. This patent discloses a cleaner casing such as indicated by 35, which has spouts 36 leading from the lower side thereof for directing blasts of air downwardly onto the top of the creel boards 16 and other portions of the textile machine. The casing 35 is supported by wheels 37, which are mounted upon tracks 38 and 39, said tracks being disposed above a textile machine and supported by posts 40 which posts also support the creel boards 16.

By referring to Figure 4, it is seen that the trackway is continuous and is adapted to move over a plurality of spinning frames 11. As heretofore stated, it has been found that a cleaner such as shown on a trackway disposed above the machine fails to provide the necessary currents or draughts of air to remove the lint from the lower members of the machine. As a matter of fact the lower portions of the machine, that is, the portions disposed below the board 24, do not receive any draughts of air from the travelling cleaner; consequently the lint which once attaches itself to this surface remains in position until it becomes so heavy that it will eventually fall onto the floor or other portions of the machine.

In order to create the desired draughts of air in the lower portion of the machine, I have secured a pair of semi-circular bands 45 around the cylinder 21 at spaced intervals, each of said bands having a pair of fan blades 46 extending radially therefrom. When these blades are properly secured to the cylinder at the desired points, the rotation of the cylinder will direct blasts of air longitudinally of the machine and in the same direction as the direction of travel of the fan casing 35. It is seen that the fan in casing 35 will cooperate with the blades 46 on the cylinder 21 in directing the waste from the machine in a common direction.

The cleaning of the lower portion of the machine has been found to be much more effective when the lower portion thereof is encased. Therefore, suitable side plates 48 have been secured to the opposed sides of the textile machine, by means of screws 49, each side plate having a plurality of doors such as designated by reference character 50 secured thereto my means of suitable hinges 51. The upper edges of the doors 50 are adapted to abut against a longitudinal strut 53 and are held in a latched position by means of suitable latches 54. The lower portion of the side plates 48 have adjustably secured thereto a plurality of plates 55 by any suitable means such as screws 56. The screws 56 penetrate slots 57 in each end of these plates and hold the lower edges of the plates a short distance above the floor level. This provides a slot 58 through which the dust and lint which has fallen upon the floor and in the aisles between the machines may be drawn by the suction created by a fan 60. The fan 60 has an inlet pipe 61 leading therefrom which is connected 75 to opening 62 in the floor 10. When this fan

is in operation the air is drawn from the opening 62 and through the fan from whence it is expelled through its outlet 63. The action of the fan 60 is supplemented by the normal excess atmospheric pressure within the room during the period that the machine is in operation, and this normal excess pressure helps to direct the lint to the opening 62. When it is desired to doff packages 27 it is only necessary to unlatch the doors 50 by operating the latch 54 after which the door can be rotated to dotted line position as shown in Figure 3. This not only will allow the packages 27 to be doffed but will also serve to give access to the lower portions of the textile machine.

In the drawings and specification there has been set forth a preferred embodiment of the invention, and although specific terms are employed, they are used in a generic and descriptive sense only, and not for purposes of limitation, the scope of the invention being set forth in the appended claims.

I claim:

1. In a fiber drawing machine having a framework and a roll stand board substantially covering the top of the framework and having a cylinder and rotary package holders driven by the cylinder for receiving yarn being processed on the machine, means enclosing the sides of the machine from a point substantially level with the roll stand board to within a short distance of the bottom of the machine, a plurality of fans mounted on the cylinder for creating drafts of air moving towards one end of the machine for removing lint and other particles from the portions of the machine disposed below the roll stand board, and suction means communicating with the interior of the machine for withdrawing removed lint from beneath the machine and for creating an inwardly moving draft from the exterior of the machine to the interior thereof through the slots appearing below the lower edge of the encasing means to thereby cause lint and other particles on the floor adjacent the sides of the machine to be drawn beneath the machine and into said suction means.

2. Apparatus for removing lint and other particles from the lower portions of spinning frames and the like, comprising sheet members closing the sides of the machine and leaving slots at the top and bottom portions of the machine, a cylinder extending longitudinally of the machine, a plurality of disk fans mounted on said cylinder for creating drafts of air moving longitudinally of the machine.

3. Apparatus for removing lint and other particles from the lower portions of spinning frames and the like, comprising sheet members closing the sides of the machine and leaving slots at the top and bottom portions of the machine, a cylinder extending longitudinally of the machine, and a plurality of disk fans mounted on said cylinder for creating drafts of air moving longitudinally of the machine, and a suction pipe communicating with the interior of the machine for removing from the interior of the machine the lint and other particles dislodged from the lower portion of the machine by the drafts of air created by said fans.

4. In a spinning machine and the like, a framework, a plurality of driven disk fans disposed within the lower portion of the machine, means substantially enclosing the lower portion of the machine and providing slots near the top and bottom of the machine, and suction means com-

5. municating with the floor level on which the machine is located for removing floating lint from the interior of the lower portion of the machine and for also creating an inwardly moving draft of air to withdraw lint from the floor spaces on each side of the machine beneath the machine and outwardly through said suction means.

5. 6. In a spinning machine having a framework comprising enclosed end portions, a creel board, a roll stand supporting board substantially enclosing the top of the machine at a point below the creel boards and also having drawing rolls and spindles and a longitudinally disposed cylinder having belts thereon for driving the spindles, plate members secured to the sides of the machine and extending to within a short distance of the floor on which the machine is disposed and having their upper edge extending to a point substantially the height of the roll stand supporting board, a plurality of fans mounted on said cylinder for creating drafts of air moving towards one end of the machine to dislodge lint and other particles from the parts of the lower portion of the machine and for moving longitudinally of the 25 machine any lint and other particles entering

the lower portion of the machine through the openings at the top of the plate members, a suction pipe having its intake end disposed at the floor level at one end of the machine towards which the drafts of air created by said fans are moving to remove from beneath the machine the lint propelled by said fans and also to draw beneath the machine, below the lower edges of the plate members, any lint which may be disposed on the floor on each side of the machine. 10

6. A spinning machine having its sides enclosed and provided with slots near the top and bottom portions thereof, a plurality of fans disposed within the enclosed machine for creating drafts of air moving towards one end of the machine, 15 and a suction pipe having its intake end disposed level with the floor for withdrawing lint from the interior of the machine and creating inwardly moving drafts of air at the bottom and top portions of the machine for drawing into the machine and outwardly through said suction pipe, lint which may be disposed adjacent said openings.
